UNITED STATES PATENT OFFICE.

THOMAS A. BAKER, OF HONESDALE, PENNSYLVANIA, ASSIGNOR TO
T. B. CLARK & CO., OF SAME PLACE.

DESIGN FOR GLASSWARE.

SPECIFICATION forming part of Design No. 18,621, dated September 25, 1888.

Application filed August 18, 1888. Serial No. 283,132. Term of patent 3½ years.

To all whom it may concern:

Be it known that I, THOMAS A. BAKER, of Honesdale, in the county of Wayne and State of Pennsylvania, have invented and produced 5 a new and original Design for Glassware, of which the following is a specification.

The drawings represent in Figure 1 a bottom view of a glass dish containing the design, and in Fig. 2 a transverse section.

10 The design is applicable to any kind of glassware, such as bowls and shallow dishes, and stemware, decanters, jugs, &c. The double-grooved lines *a a* produce two large intersecting triangles, which form the six-pointed 15 star, the points touching the circumference of the circle. Intersecting the star are three figures, *b*, composed of parallel lines curved near their ends, so as to terminate in a Gothic point, as shown, each of such points touching 20 the circumference half-way between two of the points of the star. The spaces, *c*, bounded by the lines of the star and the Gothic figures, are of fan shape, and are grooved on the surface, as at *d*, and indented or recessed on the 25 periphery, as at *e*. The interior spaces, *f*, produced by the figures described are consequently the frusta of hexagonal pyramids, the surfaces of which are ornamented by inter-

secting cross-hatching, as at *g*, or by multi-pointed stars, as at *h*. The spaces, *i*, bounded by the lines of the triangles forming the points of the star are pentagonal, while those just within the Gothic terminations of the figure *b* are quadrangular, and their surfaces are similarly ornamented. The lines forming all 30 these figures are double—that is, they consist of two closely-placed parallel V-shaped grooves, forming a central ridge, *k*—and these lines and ridges, intersecting, necessarily produce a number of four-sided pyramids, one at 35 each intersection. (For examples see *l* and *m*.)

What I claim is—

The design for the surface ornamentation of glassware herein described and shown, consisting of two intersecting triangles forming 45 the six-pointed star, three intersecting double Gothic figures, and ornamented frusto-pyramidal and fan shaped figures bounded by the lines of the triangles and Gothic figures.

In testimony whereof I have affixed my signature in presence of two witnesses.

THOMAS A. BAKER.
